UNITED STATES PATENT OFFICE.

JOEL E. HUDSON, OF BATAVIA, NEW YORK.

AUTOMATIC SHIP'S BELL.

1,143,270.

Specification of Letters Patent. Patented June 15, 1915.

Application filed February 16, 1912. Serial No. 677,909.

To all whom it may concern:

Be it known that I, JOEL E. HUDSON, a citizen of the United States, residing at Batavia, in the county of Genesee and State of New York, have invented new and useful 5 Improvements in Automatic Ships' Bells, of which the following is a specification.

My invention relates to the class of bells and more specifically to means for ringing 10 ordinary ships' bells.

An object of my invention is to provide a simple means for ringing the ships' bells and the like, which consists of a solenoid which is disposed and connected so that 15 when the same is energized the clapper will be moved into engagement with the sides of the bell.

With the above and other objects in view my invention relates to such details of construction and in the arrangement and combination of parts as will be hereinafter fully described and specifically pointed out in the appended claims.

In describing my invention in detail reference will be had to the accompanying drawings wherein like characters denote like or corresponding parts throughout the several views, and in which:

Figure 1 is a vertical sectional view of 30 my invention. Fig. 2 is a vertical sectional view of the solenoid. Fig. 3 is a detail. Fig. 4 is a front elevation of a terminal box used. Fig. 5 is a plan view of the cover for the terminal box.

In reducing my invention to practice, the same is used preferably in connection with the ordinary bell as shown in the drawings. However, I desire it to be understood that it may be used in connection with any form 40 of bell now in use, without departing from the spirit thereof.

The numeral 1 designates a suitable supporting structure which supports a bell 2 through the medium of an off-set portion 3, 45 the said off-set portion being engaged by the packing material 4. The upper portion of the bell is provided with a cut-out portion 6 through which operates the core 7 of the solenoid 8, the core being connected at its lower end as shown at 9 to one end of a 50 link 10 to which is pivoted as shown at 11 an arm 10' of a bell crank lever whose other arm is a clapper arm 12. Said bell crank lever is pivoted at 13 in any suitable manner to the bell. The clapper arm has a 55 weight 14 in screw-threaded engagement

therewith for a purpose that will presently appear. Positioned upon the inner side of the bell 2 is a leaf spring 15 as shown at 16 whereby when the weight 14 is moved into 60 engagement with the sides of the bell the said spring will engage the clapper arm and thereby return, the same into the position shown in Fig. 1.

Disposed about the solenoid 8 is a suitable 65 housing 17 which is constructed preferably from brass and which supports at one side a terminal box 18, connection being had between the terminal box and the solenoid by means of the conductors 19. In Fig. 5 is 70 illustrated the top 20 of the terminal box which is provided with a cut-out portion 21 for an obvious purpose. The terminal box is further provided with the contacts 22 to which are adapted to be connected the terminals 75 from the source of power not shown.

The solenoid 8 consists of the drum 23 which is provided with an opening 24 for the reception of the core 7, the said opening being closed at the other end by means of a 80 plate 25 which carries a depending portion 26, which portion is provided with a coiled spring 27. It is readily obvious that when the core 7 engages the portion 26 the spring 27 absorbs the shock. The wiring of the 85 solenoid is covered by a sheathing 29 which has its ends connected by the threads 30 and which is provided with means for the reception of the conductors 19.

The operation of my device is as follows: 90 A button or the like is pressed from a suitable part of the ship which closes an electrical circuit through the solenoid and draws the core 7 within the same, this operation being well known in the art. As the core 7 moves 95 into the solenoid the bell crank lever is rocked whereby the weight 14 will engage the sides of the bell and the spring 15 will engage the clapper arm, whereby as the circuit is broken it will return to its former position, the incidental shock being absorbed or reduced by the spring pressed slidale member 26.

I desire to lay the greatest of stress upon the simplicity of my device and it is thought 105 that the advantages and novel features of the same will be appreciated from the foregoing disclosure.

I desire it to be understood that I may make slight changes in the construction and 110 in the arrangement and combination of parts without departing from the spirit of

my invention, provided, however, such changes fall within scope of the subjoined claims.

Having thus fully described my invention what I claim as new and desire to secure by Letters Patent is:—

1. A device as specified, including a bell open at one end, a pivoted clapper for said bell, an electro solenoid magnet mounted 10 above and concentric with the longitudinal axis of the bell, a core therefor, means connecting said core with the clapper, shock absorbing means carried by the magnet and engageable with the core at times, and means 15 carried by the bell to assist in returning of the clapper to normal position.
2. In an air bell device, a supporting structure having an opening formed therein for the reception of a packing ring, a bell 20 open at one end depending from said support having an enlarged portion formed at its upper end, said enlarged portion entering said packing ring, a housing mounted on said supporting structure, an electro solenoid magnet disposed in said housing, a plate secured to the upper portion of said magnet, said plate having a head portion connected thereto, a coiled spring engaging 25 said head portion, the core of said magnet 30 adapted to operate at bottom of the magnet and through said enlarged portion, a clapper mounted in said bell, a bell crank lever pivoted to the bell pivotally connecting said clapper and said core, and a leaf spring connected to one side of said bell adapted to be 35 engaged by said clapper during swinging movement thereof to assist its retraction to prevent prolonged ringing periods and permit quick successive operations of the bell.
4. In an air bell device, a bell having an 40 open end, means to support the bell, an elec-

tro-magnet, the core of said magnet, a bell crank lever in said bell having a clapper thereon, means operatively connecting said bell and clapper, and a yieldable device 45 against which one end of said core strikes to prevent undue shock.

4. In an air bell device, a supporting structure, a bell open at one end depending from said structure, a housing mounted 50 on said structure, an electro-magnet within said housing having its core in said bell, a bell crank lever operatively connected to said core rotated in said bell, a clapper on said lever, a drum in which said core slides 55 having the electro-magnet wound thereon, a yieldable device supported by said drum and mounted in the path of movement of said core to be struck by one end of said core to prevent undue shock, a sheathing for said 60 magnet, means fastening said sheathing around said magnet, a terminal box connected to said housing, the terminals from said box extending through said sheathing to said magnet.

5. In an air bell device, a body of said bell having an aperture in the upper end thereof, a clapper pivoted in said bell, an electro solenoid magnet concentrically mounted over 70 said aperture, a core for said electro solenoid magnet extending through said aperture and relatively connected to said clapper, a spring retarded plunger carried by said electro magnet and engageable at times by the core 75 of said magnet to assist the clapper in returning to normal position after each impulse, as and for the purpose set forth.

JOEL E. HUDSON.
